(57) **CLAIM**

The ornamental design for a toy set, as shown and described.

DESCRIPTION

FIG. 1 is a perspective view from above of a toy set showing my new design;

FIG. 2 is a perspective view of a case;

FIG. 3 is a perspective view from below thereof;

FIG. 4 is a front view thereof;

FIG. 5 is a back view thereof;

FIG. 6 is right side view thereof;

FIG. 7 is a left side view thereof;

FIG. 8 is a top view thereof;

FIG. 9 is a bottom view thereof;

FIG. 10 is a perspective view of a first toy;

FIG. 11 is a perspective view from behind thereof;

FIG. 12 is a front view thereof;

FIG. 13 is a back view thereof;

FIG. 14 is a left side thereof;

FIG. 15 is a right side view thereof;

FIG. 16 is a top view thereof;

FIG. 17 is a bottom view thereof;

FIG. 18 is a perspective view of a second toy;

FIG. 19 is a perspective view from behind thereof;

FIG. 20 is a front view thereof;

FIG. 21 is a back view thereof;

FIG. 22 is a left side view thereof;

FIG. 23 is a right side view thereof;

FIG. 24 is a top view thereof; and,

FIG. 25 is a bottom view thereof.

The broken line showing of the toy set is for the purpose of illustrating portions of the article that forms no part of the claimed design.

1 Claim, 20 Drawing Sheets
